UNITED STATES PATENT OFFICE.

OLLIE W. BRADSHER, OF HARRISBURG, ARKANSAS.

SELF-LOADING VEHICLE.

1,157,291.

Specification of Letters Patent.

Patented Oct. 19, 1915.

Application filed February 18, 1915. Serial No. 9,109.

To all whom it may concern:

Be it known that I, OLLIE W. BRADSHER, a citizen of the United States, residing at Harrisburg, in the county of Poinsett and State of Arkansas, have invented certain new and useful Improvements in Self-Loading Vehicles, of which the following is a specification, reference being had to the accompanying drawings.

This invention relates to certain improvements in self-loading vehicles and has relation more particularly to a device of this general character including a scoop; and an object of the invention is to provide a device of this general character having novel an improved means whereby the body of the vehicle may be adjusted with convenience and facility relative to the surface to be engaged thereby.

Furthermore, it is an object of the invention to provide a vehicle of this general character whereby the material deposited within the body thereof may be caused to move rearwardly.

It is also an object of the invention to provide means whereby the rearwardly movable material may be pulverized, said pulverizing means being also capable of adjustment relative to the material with which it coacts.

It is a further object of my invention to provide a vehicle of this general character having novel and improved means whereby the material deposited within the body of the vehicle may be distributed with convenience and facility and especially when employed in connection with fertilizer or the like.

The invention consists in the details of construction and in the combination and arrangement of the several parts of my improved self-loading vehicle whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be better understood, I will now proceed to describe the same with reference to the accompanying drawings, wherein—

Figure 1 is a view in side elevation of a self-loading vehicle constructed in accordance with an embodiment of my invention

and adjusted into operative position; Fig. 2 is a longitudinal vertical sectional view taken through the device as herein embodied and with the body or apex 3 in an elevated position. Fig. 3 is an enlarged fragmentary sectional view taken longitudinally of the bed of the vehicle body; Fig. 4 is an enlarged fragmentary transverse sectional view of the vehicle body; Fig. 5 is a fragmentary view in perspective illustrating in detail a mounting included in the feeding or pulverizing mechanism herein embodied; Fig. 6 is an enlarged view, partly in elevation and partly in section, illustrating the driving means for the feeding or pulverizing mechanism herein set forth; Fig. 7 is an enlarged fragmentary view in top plan illustrating in detail a mounting for certain of the controlling levers herein set forth; Fig. 8 is a transverse sectional view taken through the body of the device adjacent the discharge end thereof; and Fig. 9 is a fragmentary view in elevation of the rear of the vehicle opposite to that shown in Fig. 1.

As disclosed in the accompanying drawings, 1 denotes a rear axle having rotatably mounted thereon the supporting wheels 2 and to which is fixedly engaged the vehicle body or box 3, said body being adapted for rocking movement relative to the wheels 2, and having its opposite ends open, the rear end being adapted to be closed by the end gate 4 in a manner to be hereinafter more particularly referred to. The box or body 3 of the vehicle may be constructed in any manner desired, as I do not wish to be understood as limiting myself in any way as to the specific construction thereof. I also find it of advantage to have the body or box 3 operatively engaged intermediate its length with the axle 1, as is clearly shown in the accompanying drawings.

5 denotes a forward arched axle provided with suitable supporting wheels 6 and having operatively engaged therewith the draft rigging 7 which may be of any ordinary or preferred construction, and said forward axle 5 has coacting therewith suitable brace members 5^a, for a purpose which is believed to be self-evident. Pivotaly engaged with the forward axle 5 are the extremities of the arms 8, the opposite extremities of said arms being pivotally engaged with the sides of the box or body 3 at a point intermediate the axle 1 and the forward end thereof whereby it will be perceived that upon

proper manipulation of the arms 8, the forward extremity of the box or body 3 may be adjusted with convenience and facility relative to the surface over which the device is adapted to travel.

- 5 As herein disclosed, projecting upwardly from the arms 8 are supporting members 9 having pivotally engaged therewith the double lever 11, the extremities whereof being operatively engaged through the medium of the links 12 with the sides of the box or body 3 at the forward end thereof whereby it will be perceived that upon inward movement being imparted to the upper extremity of the lever 9, the box or body 1 may be caused to assume a substantially horizontal position. The lever 9 coacts with the racks 14 operatively supported by one side of the box or body 3 and the upper extremity of an adjacent supporting member 9 whereby it will be perceived that the box or body 3 may be locked or maintained in its varying adjustments in a conventional or well known manner.
- 10 Pivots supported with the front or forward extremity of the box or body 3 is the scoop member 15 adapted to engage the surface over which the device is drawn in order to fill or load the box or body 3, and in order that such scoop 15 may be raised or lowered as desired, I also have pivotally engaged with the members 9, a double lever 16, the extremities whereof being operatively engaged with the scoop through the medium of the links 18, said lever coacting in a conventional way with racks 14, hereinbefore referred to. The box or body 3 at a point intermediate its forward end and the axle 1 is provided with a seat structure S, and it is to be particularly noted that the upper extremities of the levers 11 and 16 are in close proximity thereto in order that they may be readily and conveniently manipulated by the operator. It will also be seen that when the scoop 15 is in its vertical adjustment, it serves as a front end gate for the box or body 3.

Disposed transversely of the box or body 3 are the shafts 20 provided with the sprockets 21 around which are directed the endless sprocket chains 22 tied or connected by the transverse slats 23 whereby it will be perceived that a movable floor is afforded for the box or body 3 and which is adapted to travel rearwardly thereof so that the material deposited within the box or body 3 by the scoop 15 is conveyed rearwardly so that, when required, the box or body 1 may be completely filled. The rear shaft 20 projects beyond opposite sides of the body or box 3 and has loosely mounted on each projected extremity thereof, the gear 24 provided with the clutch face 25 with which is adapted to coact the clutch member 26 keyed to the shaft 20 but capable of move-

ment longitudinally thereof, said movement being under control of the lever 27. The gear 24 is in mesh with an idle gear 28 rotatably supported by the box or body 3 and integrally produced with the gear 28 is the sprocket 29 around which is directed an endless sprocket chain 30 also disposed around the drive sprocket 31 carried by one of the supporting wheels 2. I also find it of advantage to have disposed transversely of the bottom of the box or body 3, the idle rollers 32 over which travel the endless chains 22, and to have positioned transversely of the body and therebeneath the idle rollers 34 over which the movable floor 30 passes and which serve to prevent undue sagging of the under or return stretch thereof.

Disposed transversely across the box or body 3 at predetermined intervals longitudinally thereof are the bars 35 from which depend the rigid arms 36 positioned adjacent the opposite sides of the body or box 3 and having rotatably supported in their lower extremities the rollers 37 provided with the radially disposed teeth 38, said rollers 37 with their teeth 38 serving as pulverizing members for the material passing therebeneath, and which also serve as an additional means for forcing rearwardly the material delivered by the scoop 15. Also operatively supported by the bars 35 is the longitudinally disposed shaft 39 having fixed thereto gears 40 in mesh with the gears 41 loosely mounted on the bars 35. Each of the gears 41 has movable therewith a sprocket 42 around which is disposed a chain 43 also directed around a sprocket 44 fixed to the coacting roller 37 whereby it will be perceived that upon imparting axial rotation to the longitudinally disposed shaft 39, the rollers 37 will be caused to simultaneously rotate. As herein embodied, the rear extremity of the horizontally disposed shaft 39 is provided with a gear 45 in mesh with a gear 46 fixed to the transversely disposed shaft 47 carried by the box or body 3 and provided at one extremity with the sprocket 48 around which is disposed a sprocket chain 49 also directed around a sprocket 50 carried by a projected extremity of the rear shaft 20.

The rigid arms 36 are fixed to the bars 35, said bars being freely rotatable, and it will thus be seen that the rollers 37 will automatically move upwardly or downwardly as the thickness of the layer of the material carried by the movable floor increases or decreases.

In practice, I find it of advantage to have each of the rollers 37 mounted upon stationary shafts 51 and to provide such shafts 51 with the anti-friction members 52 adapted to engage the sides of the box or body 3 so that the rollers 37 may move upwardly

or downwardly with a minimum of frictional resistance. I also find it of advantage to provide means whereby the rollers 37 may be positively moved relative to the 5 movable floor and, as herein embodied, I provide each of the bars 35 with the rearwardly disposed arm 53 provided in its free extremity with an elongated slot 54 adapted to receive the lateral projection 10 55 carried by the rod 56 depending from an elongated arm 57 mounted for reciprocatory movement longitudinally of the box or body 3. By this arrangement, it will be seen that 15 movement of the rod 56 in one direction will cause the rollers 37 to be elevated, while movement in the opposite direction will cause the rollers to be lowered.

It is also a purpose of my invention to employ my machine as a distributor for fertilizer or the like. For that reason I have disposed, at the rear or tail of the box or body 3, the vertically spaced toothed rollers 58 operatively connected, as at 59, whereby the same may be caused to rotate in unison, 25 and one of said rollers, as at 60, is operatively engaged with the rear shaft 20, it being understood that when my improved device is employed as a distributor, the end gate 4 is adjusted into an open position under 30 the influence of the lever 61.

Coacting with the upper stretch of the movable floor adjacent the rear extremity of the body or box 3 is the scraper member 62 pivotally supported by the sides of the 35 box or body 3 and disposed transversely on a suitable incline, the longitudinal edge thereof being maintained in engagement with the top surface of the upper stretch of the movable floor through the medium of 40 the retractile members 63, herein disclosed as conventional coil springs, secured to the scraper at predetermined points and to the sides of the box or body 3. I prefer to have this scraper positioned below the end gate 45 4 whereby it will be perceived that such scraper will not interfere with the passage of the movable floor around the rear shaft 20 and it will also be observed that this scraper member 62 does not materially interfere 50 with the discharge of the material within the body or box 3.

From the foregoing description, it is thought to be obvious that a self-loading vehicle constructed in accordance with my invention is particularly well adapted for use 55 by reason of the convenience and facility with which it may be assembled, and it will also be obvious that my invention is sus-

ceptible of some change and modification without material departure from the principles and spirit thereof and for this reason I do not wish to be understood as limiting myself to the precise arrangement and formation of the several parts herein shown in carrying out my invention in practice. 60 65

As herein embodied, each of the racks 14 comprises a segmental toothed portion 64 pivoted at one extremity, as indicated at 65, to a side of the vehicle body and having its opposite extremity provided with an elongated segmental slot 66 through which is projected a pin 67 carried by the upper extremity of the extension 68 of the adjacent supporting member 9. It is also to be observed that the levers 11 and 16 are pivotally engaged with the shaft 10 connecting the supporting members 9 adjacent the upper extremities thereof. 70 75

I claim:

1. In combination, a wheel supported 80 shaft, a body mounted upon said shaft and capable of rocking movement thereon, the forward end of said body being open, a forward wheel supported axle, supporting members projecting upwardly from the 85 arms, a double lever pivotally engaged with the supporting members, the lower extremities of said lever being operatively engaged with the body at a point in advance of the pivotal connection between the arms and the 90 body, coacting locking means carried by the lever and the body, and a ground engaging element carried by the forward extremity of the body. 95

2. In combination with a body, a plurality 95 of bars disposed transversely thereof and arranged in predetermined longitudinal adjustment and capable of rocking movement, rock arms depending from the bars, pulverizing rollers rotatably mounted in the lower 10 extremities of the rock arms, means common to each of the bars for imparting rocking movement thereto whereby the pulverizing rollers may be raised or lowered, a rotatable element loosely mounted on each of the bars, an operative connection between said element and the adjacent roller, and means common to each of the elements for rotating the same in unison. 110

In testimony whereof I hereunto affix my 110 signature in the presence of two witnesses.

OLLIE W. BRADSHER.
